CLAIM

We claim the ornamental design for a biomonitoring sensor system for monitoring body chemistry, as shown and described.

DESCRIPTION

FIG. 1 is an isometric view, from the top right, of the biomonitoring sensor system.

FIG. 2 is an isometric view, from the bottom left, of the biomonitoring sensor system.

FIG. 3 is a plan view of the top of the biomonitoring sensor system.

FIG. 4 is an elevation view of the right side of the biomonitoring sensor system.

FIG. 5 is an elevation of the front of the biomonitoring sensor system.

FIG. 6 is a plan view of the bottom of the biomonitoring sensor system.

FIG. 7 is an elevation view of the back of the biomonitoring sensor system; and,

FIG. 8 is an elevation of the left side of the biomonitoring sensor system.

Any broken lines are understood to be for illustrative purposes only and form no part of the claimed design.
